UNITED STATES PATENT OFFICE

JENS N. JACOBSEN, OF ALAMEDA, CALIFORNIA, ASSIGNOR TO THE PFAUDLER COMPANY, OF ROCHESTER, NEW YORK, A CORPORATION OF NEW YORK

HEAT-TRANSFER APPARATUS

Application filed June 6, 1927. Serial No. 196,688.

This invention relates to heat exchangers and particularly to heat exchangers of the type in which the fluid to be heated or cooled is passed through tubes which are immersed in a heating or cooling fluid.

An object of this invention is to provide an apparatus of the above type which is capable of thoroughly efficient and dependable operation. Another object is to provide a heat exchanger which is of simple and durable construction and which may be quickly and conveniently assembled or dismantled. Another object is to provide improved means for imparting rotational movement to the body of heating or cooling fluid as it passes through the heat exchanger. Another object is to provide means for removing gases from the heat exchanger. Another object is to provide an improved structure for permitting expansion and contraction of the tubes without damage to the apparatus. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the drawings in which is shown one of the various possible embodiments of this invention,

Figure 1 is a side elevation of the assembled apparatus;

Figure 2 is a plan view of the assembled apparatus;

Figure 3 is an end elevation of the apparatus;

Figure 4 is a longitudinal section taken substantially on the line 4—4 of Fig. 2;

Figures 5 and 6 are views of the end doors, taken substantially on lines 5—5 and 6—6 of Figure 4;

Figure 7 is a transverse sectional view taken substantially on line 7—7 of Figure 4; and

Figure 8 is a fragmentary sectional view showing the tube, header, and end door assembly, portions of the tubes being broken away.

Similar reference characters refer to similar parts throughout the several views of the drawings.

The heat exchanger of this application comprises two main units which may be termed a drum or jacket and a tube assembly. The drum comprises an inner tubular shell 10 having hollow annular manifolds 11 and 12 attached thereto at opposite ends and an outer shell 13 which extends over the manifolds and encloses the inner shell. The inner and outer shells are spaced apart.

The tube assembly comprises apertured header members 14 and 15, a plurality of tubes 16 having their opposite end portions fixed within the apertures in the headers, and recessed door members 17 and 20. The inner surfaces of the door members between the cavities and the outer surfaces of the header members between the apertures are ground to provide smooth plane surfaces which are adapted to lie fully in contact with each other when the doors are applied to the headers. Thus, the necessity for the provision of the usual sealing gasket of rubber or other pliable substance is eliminated. T-bolts 21 pivoted on brackets 22 carried by the header members are adapted to enter slots formed in the brackets or lugs 23 carried by the door members and, with the nuts 24, serve to clamp the door members in position on the header members. The cavities and apertures of the door and header members are so arranged that a fluid entering, for instance, through the conduit 25 mounted in the threaded aperture 26 in the door member 20 will pass successively through each tube 16 and out of the apparatus through the conduit 27 mounted in a second threaded aperture 30 in the door member 20. For convenience the door members may be removably hinged and latched as at 31 and 32.

One of the important features of this apparatus is the structure which permits the tube assembly to be removed as a unit from the drum for cleaning and other repair purposes. The header 15 and door 20 are of such sizes that when mounted on the tubes they may be passed through the drum to their normal operative positions as shown in Figure 100

4. The flange 33 carried by the header 14 limits the movement of the tube assembly, and bolts 34 passing through the flange 33 and entering the manifold 11 are provided for locking the tube assembly in position in the drum. The flange 33 and the inwardly projecting annular shoulder 35 fit tightly against the manifold and provide a leak-proof joint. A flexible connection between the drum and the opposite end portion of the tube assembly is provided for permitting longitudinal expansion of the tubes without injury to the apparatus. The smooth outer surface of the inner end portion of the header 15 makes a sliding contact with the smooth inner surface of the annular flange 36. The stuffing box 37 and the sliding contact between the header 15 and flange 36 permit movement of the header 15 relatively to the manifold 12 as the tubes expand or contract as a result of temperature changes.

By merely removing the bolts 34 the entire tube assembly may be disconnected from the drum, and, when the conduits 25 and 27 are disconnected in any suitable manner, the entire tube assembly, including the tubes, headers, and doors, may be withdrawn from the drum as a unit. If desired, the door 20 may be disconnected from the header 15 before the tube assembly is removed.

In the embodiment shown in the drawings the apparatus is adapted for use in raising the temperature of a fluid passing through the tubes 16. Water, to be used as a heating medium may be introduced to the interior of the shell 10 through the connection 40 at the bottom portion of the drum. The manifolds at the opposite ends of the drum are connected through the horizontal conduit 41, the L-shaped conduit 42 and stand-pipe 43 which communicates with the hollow interior of the manifold 11 at the top thereof. An overflow pipe 44 communicates with the interior of the stand-pipe at a point above the point of connection of the L-shaped conduit with said stand-pipe. The conduit 41 is provided with a steam connection 45 which carries a steam nozzle 46. The steam nozzle 46 projects within the conduit 41 to a point beyond the point of connection of the L-shaped conduit with said horizontal conduit.

When the apparatus is in use, the tubes may be connected in any suitable manner with a source of supply of the fluid to be heated. The system is filled with the heating medium to a level above the point of connection of the L-shaped conduit with the stand-pipe. Since the system is normally closed except for the steam inlet and the stand-pipe overflow, a current of steam issuing from the nozzle 46 will cause a circulation of the heating liquid through the system. The steam will force the heating liquid along the conduit 41 into the drum through the manifold 12 and out of the

drum to the conduit 41 through the manifold 11 and conduit 42.

The body of heating liquid in passing through the drum will have a rotational movement due to the effect of the slots 47 in the inner wall of the manifold 12. The heating liquid entering the drum through the said slots or passages will be given a rotational movement about the longitudinal axis of the drum which will be maintained during the passage of the liquid through the drum. The slots or passages in the inner wall of the manifold 11 may be disposed similarly to those in the manifold 12, or they may be oppositely disposed to aid in the elimination of the heating liquid from the drum. The rotational movement insures uniform mixing and rapid and thorough circulation of the heating fluid over the surfaces of the tubes. Thus, a highly desirable rate of exchange of heat may be obtained, since the rate of exchange of heat between liquids on opposite sides of a wall is proportional to the rates of movement and through agitation of the liquids.

The steam which enters the system is condensed, and, as the amount of water in the system builds up through condensation of the steam, the excess flows out through the overflow pipe 44. As a result of the provision of the stand-pipe 43 and overflow pipe 44, it is possible to maintain constant pressure in the system which factor aids in maintaining the desired temperature regulation.

A considerable amount of air or other gases may enter the system with the steam and if no provision is made for its elimination it may collect in various portions of the apparatus and prevent the heating fluid from completely covering the tubes, thereby reducing the efficiency of the apparatus. For the purpose of eliminating gases from the system, there is provided a gas conduit 50 which communicates with the stand-pipe 43 and with the interior of the drum adjacent its highest point. Gases which enter the drum are conducted through the conduit 50 to the stand-pipe and out the overflow pipe 44 to the atmosphere.

From the foregoing, it will be seen that there is herein provided an apparatus which embodies the features of this invention and achieves the objects thereof. A heat transfer apparatus is provided which is of simple and durable construction and thoroughly efficient and dependable in operation.

As many possible embodiments may be made of the above invention, and as many changes might be made in the embodiment above set forth, it is to be understood that all matter hereinbefore set forth or shown in the accompanying drawings is to be interpreted as illustrative and not in a limiting sense.

I claim as my invention:

1. A heat transfer apparatus comprising a drum for receiving a fluid, conduit means communicating with the interior of said drum at spaced points, means for circulating a fluid through said drum and said conduit means, and means for giving the fluid a rotary motion in said drum. 70
2. A heat transfer apparatus comprising a drum, a plurality of tubes for receiving a fluid to be treated positioned within said drum, conduit means communicating with the interior of said drum at spaced points, means for circulating a treating fluid through said drum and said conduit means, and means for giving the treating fluid a rotary motion in said drum. 75
3. A heat transfer apparatus comprising a drum, a plurality of tubes for receiving a fluid to be treated mounted within said drum, conduit means communicating with the interior of said drum at spaced points, means for circulating a treating fluid through said drum and said conduit means and means for agitating said treating fluid. 80
4. A heat transfer apparatus comprising a drum, a conduit communicating with the interior of said drum at spaced points, means for introducing steam into said conduit, and a stand pipe communicating with the interior of said drum. 85
5. A heat transfer apparatus comprising a drum, a conduit communicating with the interior of said drum at spaced points, a stand-pipe communicating with the interior of said drum, and a gas conduit communicating with said stand-pipe and the interior of said drum. 90
6. In a heat transfer apparatus, a drum comprising a tubular body portion and a hollow annular manifold having slots formed in its inner wall, and a conduit having one end portion communicating with the interior of said manifold and its opposite end portion communicating with the interior of said body portion at a point spaced from said manifold. 100
7. A heat transfer apparatus comprising a drum, a plurality of tubes mounted within said drum, and means for circulating a fluid within said drum around said tubes, said means including a channel extending around the periphery of said drum and having a plurality of ports establishing communication between said channel and the interior of said drum, each of said ports being arranged at an acute angle to a line drawn perpendicular to the wall of said peripheral channel at said port. 115
8. A heat transfer apparatus comprising a drum, a plurality of tubes mounted within said drum, and means for circulating a fluid around said tubes within said drum, said means including a conduit extending circumferentially around said drum and separated from the interior of said drum by a wall, and a plurality of slots extending through said wall to establish communication between said conduit and the interior of said drum, said slots being arranged at an acute angle to the radii of said wall so that fluid passing through said slots travels substantially in a tangential direction. 120
9. A heat transfer apparatus comprising a plurality of tubes for receiving material to be treated, a substantially horizontally arranged jacket surrounding said tubes, conduit means connected to the top of said jacket adjacent one end thereof and also connected to said jacket adjacent the other end thereof, and means for circulating a fluid through said jacket and conduit means. 125
10. A heat transfer apparatus comprising a plurality of tubes, a jacket surrounding said tubes, conduit means connected to said jacket at spaced points, means for circulating a fluid through said jacket and conduit means, and agitating nozzle means for causing agitation of the circulated fluid around said tubes within said jacket. 130
11. A heat transfer apparatus comprising a plurality of tubes, a jacket surrounding said tubes, a standpipe connected to the top of said jacket adjacent one end thereof, conduit means connecting said standpipe to said jacket adjacent the other end thereof, and means for circulating a fluid through said jacket and conduit means. 135
12. A heat transfer apparatus comprising a plurality of tubes, a jacket surrounding said tubes, a standpipe connected to said jacket adjacent one end thereof, conduit means connecting said standpipe to said jacket adjacent the opposite end thereof, and a connection from an intermediate point of said jacket to said standpipe. 140
